BOILER ASSEMBLY

Harry S. Murphy, Attica, N. Y., assignor to
 Cooney Refrigeration Company, Inc., Buffalo,
 N. Y., a corporation of New York

Application March 31, 1937, Serial No. 134,103

10 Claims. (Cl. 122—225)

This invention relates to a combustion chamber for boilers particularly designed to be used in connection with the sectional boiler shown in my co-pending application Ser. No. 106,570, filed October 20, 1936.

The sectional boiler forming the subject of my said copending application comprises a boiler composed of similar sections arranged side by side to form the combustion chamber and flues of the boiler and each vertical section is in turn composed of a plurality of smaller sections so formed that both the water and hot gases are required to traverse a circuitous path, crossing and recrossing one another in a generally vertical course through each vertical section and both in intimate contact with large areas of common walls so that a high rate of heat transfer is obtained resulting in quick pickup, longer off-firing periods, and low flue gas temperature, thereby providing low fuel consumption.

A further feature of the boiler forming the subject of my said co-pending application is the provision of a restricted central water orifice in each section at the point of impingement of the hottest gases, this restricted orifice causing steam to be formed and the water jetted violently therethrough, thereby creating a violent turbulence which improves the heat transfer between the boiler walls and the water and permits of a reduction in the amount of boiler surface.

It is the principal object of this invention to provide a combustion chamber composed of refractory brick which becomes heated to a high temperature and is formed to provide passages through which the products of combustion escape before contacting the boiler, the high heat of the refractory material forming the combustion chamber serving to insure complete combustion of the gases before leaving the combustion chamber, thereby securing the maximum fuel economy and avoiding carbon deposits within the boiler.

Another object of the invention is to provide such a combustion chamber which is extremely simple in construction and is made principally of standard fire brick and a plurality of identically formed, specially molded panels. By this means the only special parts needed in fabricating a combustion chamber in accordance with my invention are a plurality of identical panel sections which when arranged upon an enclosing wall of fire brick provide the restricted passages necessary to insure complete combustion of the fuel.

Another object of the present invention is to provide such a combustion chamber in which restricted passages are provided which discharge

the hot gases against the center of the boiler, thereby intensifying the jetting effect of the central water nozzle or restricted orifice disclosed in my said co-pending application.

Another object of the present invention is to provide a roof for a combustion chamber which is composed of a plurality of recessed slabs forming passages for the escape of the products of combustion and in which the end dimensions of the slabs are the same as the face dimensions of standard refractory brick, thus permitting the slabs to be built into the brickwork in the same manner as the bricks themselves.

Another object is to provide such a combustion chamber which can be rapidly fabricated at low cost and will stand up under constant use at high temperatures without breaking down or losing efficiency.

In the accompanying drawings:

Fig. 1 is a vertical transverse section, through one vertical section of a sectional boiler mounted on the wall of a combustion chamber made in accordance with my invention.

Fig. 2 is a side elevation of the combustion chamber and sectional boiler mounted thereon.

Fig. 3 is a vertical central section, taken on line 3—3, Fig. 1.

Fig. 4 is a fragmentary front elevation of the combustion chamber.

Fig. 5 is a horizontal section, taken on line 5—5, looking downwardly.

Fig. 6 is a fragmentary vertical section, taken on line 6—6, Fig. 1.

Fig. 7 is a perspective view of one of the panels used to form the top of the combustion chamber.

The boiler in connection with which the combustion chamber forming the subject of the present invention is designed for use is preferably constructed as follows:

The boiler is composed of a plurality of identical sections 10, 10a and 10b which, as indicated in Figs. 2 and 3, are arranged side by side and each of these sections is composed of a lower horizontal section 13 and a generally T-shaped main section 14 having the central portion of its base connected to and supported by the lower section 13. Each lower section 13 is formed at its opposite ends to provide a short water leg 15 each of which is provided in its front and rear walls with relatively large holes 17. The holes 17 all register with one another so that when the sections 13 are arranged face to face, as illustrated in Figs. 2 and 3, the openings 17 provide continuous conduits from one end of the boiler to the other for distribution of the cold water to each of the water

- legs. The holes 17 also serve as a means for securing the several sections together in a watertight manner. For this purpose slip nipples (not shown) can be secured in the registering openings 17 and suitable tie rods (not shown) are also preferably employed. The section 13 is made in the form of a hollow casting, rectangular in cross section, and to permit the products of combustion to escape vertical tubular flues 21 and 22 are provided at each end thereof. These flues 21 and 22, as illustrated in Fig. 3, are of smaller external diameter than the internal space across the section 13 so that the water is free to flow from the legs 15 to the center of the section 13. At its center the section 13 is provided in its top wall with a threaded opening receiving a nipple 23 which connects the lower section 13 with the main section 14 and forms a restricted conduit for conducting the water to the main section 14.
- 20 The main section 14 is in the form of a generally T-shaped hollow casting including a central Y-shaped portion 25, the base 26 of which is connected to the lower section 13 by the nipple 23 and the rounding arms 27 of which terminate in lateral extensions 28 and 29. In spaced relation to the central Y-shaped portion 25, the main section 14 is formed to provide an upper horizontal cross bar 30, vertical hollow bars 31 and 32 and inwardly extending hollow bars 33 and 34 which 25 extend under the lateral extensions 28 and 29 of the central Y-shaped portion 25.
- 30 The flow of water from the central Y-shaped portion 25 to the surrounding C-shaped portion formed by the bars 30—34 is effected by a pair 35 of hollow vertical webs 35 and 36. The rear faces of these webs 35 and 36 are co-planar with and form continuations of the rear faces of the bars 30—34 and the base of the central Y-shaped portion 25 and form connecting water passages 40 therebetween. The outer vertical sides of the webs 35 and 36 are also preferably spaced from the vertical side bars 31 and 32 to form rectangular openings 37, 38 through the back of each main section 14. The hollow webs 35 and 36 are spaced from one another to form a central circular opening 40 through the back of the main section 14, and the inner walls of the arms 27 of the Y-shaped central portion 25 form continuations of this opening so as to form a main horizontal continuous flue through the group of sections 45 constituting the boiler assembly.
- 50 The arm 27 of the Y-shaped central portion 25 and its lateral extension 28 open at their rear sides into the web 35 and the lower end of this web 35 also communicates with the inward extension 33. The upper end of the hollow web 35 opens into the upper bar 30. Similarly, the other arm 27 of the Y-shaped central portion 25 and its lateral extension 29 open at their rear 55 sides into the hollow web 36; the lower end of this hollow web communicates with the inward extension 34 and the upper end of this hollow web opens into the upper bar 30 of the main boiler section 14.
- 60 The upper horizontal bar 30 is preferably provided with a raised central portion 45 at its center and the front and rear walls of the bar 30 in this raised central portion are provided with 65 openings 46. The openings 46 of the several sections register with one another in the assembled boiler so as to form a horizontal water discharge conduit extending through the several sections, and to provide a watertight connection between the several vertical section slip nipples (not 70 shown) are preferably provided in the registering openings 46.

The inward extensions 33 and 34 are higher than the base 26 of the central Y-shaped portion and to support the outer extremities of the main section 14 blocks 50 of refractory material are interposed between the extremities of the sections 13 and 14. These blocks 50 also serve to block off the ends of the horizontal passages formed between the upper and lower sections 13 and 14 and by their use the castings forming these sections are less complicated and the provision of dead water or flue pockets is avoided. Refractory blocks can also be employed to block off the front and rear ends of the chambers formed between the sections 13 and 14 in the assembled boiler.

The front faces and the rear faces, respectively, of the lower section 13; refractory blocks 50; Y-shaped central part 25 of the main section 14 and the upper bar 30; side bars 31 and 32 and extensions 33 and 34 of this main section 14 are disposed in a common plane. It will therefore be seen that when the sections 10, 10a, 10b are assembled the hot gases striking the undersides of the lower sections 13 are required to pass upwardly through the openings 21 and 22 of the lower sections 13 into the chambers 54 and 55 between the sections 13 and 14, the sides and ends of which are blocked off by the refractory blocks 50. The gases then sweep toward the inner end of each chamber 54 and 55 against the nozzle or leg 26 and against the legs 27 of the central Y-shaped portions 25 and pass out through the angular passages 56 and 57 formed between these Y-shaped portions 25 and the extensions 33 and 34. As the passages 56 and 51 are in part formed by the hollow webs 35 and 36, it will be seen that the hot gases are uniformly distributed to the many passages 56 and 57 and are prevented from sweeping to one end of the assembled boiler. From the passages 56 and 57 the gases pass upwardly through the chambers 58 and 59 which extend the full length of the boiler assembly and from these chambers the hot gases are deflected inwardly through the passages 60 and 61 between the upper bar 30 and the extensions 28 and 29 of the central Y-shaped portions 25. As these passages 60 and 61 are in part formed by the hollow webs 35 and 36 the hot gases are uniformly distributed to the passages 60 and 61 and prevented from sweeping to one end of the boiler assembly. From the passages 60 and 61, the gases sweep down into the main horizontal flue formed by the openings 40 through the several boiler sections and from one end of this main horizontal flue the gases are, of course, conducted to the usual smoke stack (not shown).

With the boiler assembled as above described, the cold water admitted at the bottom of the water legs 15 flows inwardly from the opposite extremities of the sections 13 and upwardly through the restricted nipples 23 into the bases 26 of the Y-shaped portions of the sections 14. The hottest flue gases impinge centrally against the undersides of the sections 13 and the flue gases also impinge against the sides of the base 26. The water is therefore brought to a high temperature under the nipple 23 and steam is formed, the water thereby being jetted through the nipple 23 at high velocity and being violently agitated, this turbulence of the water continuing in the upward passage of the water through the arms 27 and webs 36 of the main boiler section 75

14. This violent turbulence created by the jetting action of the nipple 23 increases the rate of heat transfer between the walls of the boiler and the water and thereby improves the efficiency 5 of heat transfer and permits a boiler having a smaller surface to be employed as compared with a boiler unprovided with the central restricted jets or nipples 23.

From the base 26 of each of the Y-shaped portions 25 the flow of the turbulent water divides into several paths. One stream passes through the branch 27 of the Y-shaped central portion 25 horizontally across the bottom of the web 35 into the inward extension 33 and thence up the 15 vertical bar 31 into the horizontal bar 30. Another stream flows up the branch 27 of the Y-shaped central portion into the lateral extension 28 and out through the upper part 20 of the web 35 into the upper horizontal bar 30. Similarly, on the other side of the boiler one stream from the base of the Y-shaped portion 25 passes generally in a horizontal direction across the bottom of the hollow web 36 into the vertical bar 32 while another stream flows vertically through the lateral extension 29 and upper part of the hollow web 36. All of these 25 streams in each section merge in the upper bar 30 and pass into the common outlet duct formed by the registering openings 46 and 47 of the several sections 10, 10a and 10b.

The combustion chamber forming the subject of the present invention is designed to insure complete combustion of the fuel and also to direct the hot gases to the center of the several 35 lower sections 13 so as to concentrate heat under the nozzle or nipple 23 and improve its jetting action in creating a high turbulence in the water. The combustion chamber includes a front wall 65 made of refractory brick of standard 40 size and having included therein a block 66 of refractory material through which fuel and air are introduced into the combustion chamber. The combustion chamber shown is designed for the use of liquid fuel. The combustion chamber is 45 provided with side walls 67 and 68 likewise made of standard refractory brick and a rear wall 69 connecting the rear ends of the side walls 67 and 68. The water legs 45 of the assembled 50 boiler rest on the side walls 67 and 68, as best illustrated in Fig. 1 and the boiler is therefore adequately supported.

The roof of the combustion chamber and also the upper portions of the front and rear walls 55 65 and 69 are formed of a plurality of identical slabs or panels 70 which are made of a refractory 60 material in the form illustrated in Fig. 7. The end dimensions of each of the slabs or panels 70 are the same as the face dimensions of the standard brick used in building the walls of the combustion chamber and the slabs 70 extend the full 65 length of the combustion chamber and are supported on the front and rear walls thereof. Each slab on one side and for the major portion of its length is recessed as indicated at 71. This recessed portion extends from a line 72 adjacent one corner of the slab to a line 73 adjacent the diagonally opposite corner of the slab so as to 70 form a flat face 74 which is disposed at an angle to the major flat faces of the slab. To permit of conveniently building the slabs into the front 75 and rear walls of the combustion chamber the end portions 75 of the slabs are of regular rectangular form and of the same dimensions as the standard bricks employed in building up the combustion chamber.

In laying a roof composed of the flat slabs 70 a pair of the flat slabs are first laid face to face with their ends supported on the bricks forming the front and rear walls 65 and 69 with the recessed portions 71 facing outwardly and upwardly 5 and the end walls are then built up with additional bricks so as to bring them to the level of the tops of these slabs. A brick of standard dimensions is then laid centrally at the opposite ends of these slabs 70 so as to bridge the abutting 10 faces of these slabs, as best illustrated in Fig. 1, and a second pair of slabs 70 is then laid alongside of these bricks. These upper slabs are therefore spaced by one brick and are also laid with their recessed portions facing downwardly 15 and inwardly so as to form slots 80 and 81 in the roof of the combustion chamber, these slots extending the full length of the combustion chamber and discharging the products of combustion 20 against the portion of the sections 13 immediately under the jets or nozzles 23.

The balance of the ends walls 65 and 69 is then bricked up or blocked off in any suitable manner to prevent the escape of the products of combustion. The products of combustion from 25 the combustion chamber are compelled to escape through the slots 80 and 81. In doing so the slabs 70 forming the roof of the combustion chamber are heated white hot. The complete combustion of the gases passing through the slots 30 80 and 81 and thereby in intimate contact with the recessed faces of the slabs 70 is therefore insured. By this means complete combustion 35 of the fuel is provided with resultant economy and carbon deposits in the passages through the boiler 40 are avoided. At the same time the slots 80 and 81 direct the intensely hot products of combustion against the center of the boiler and immediately under the jetting nozzle 23, thereby providing an intense heat at this point which 45 improves the efficiency of the nozzle or nipple 23 as a steam and water jet for creating turbulence in the main section 14 of the boiler.

From the foregoing it is apparent that the present invention provides a combustion chamber which insures complete combustion in the fuel by the provision of narrow slots through a refractory roof maintained at high temperature and also provides a combustion chamber in which the hot products of combustion can be directed against that part of the boiler which the highest degree of efficiency dictates, this being, with the boiler shown, against the portion immediately under the central nozzles or jets 23. It is also apparent that with the slabs 70 recessed as shown 50 only one type of roof slab need be provided to provide the slots or passages through the roof, these slots or passages being provided by the simple expedient of laying the upper slabs in offset and inverted relation to the lower slabs. It will also be seen that by making the end 55 dimensions of the slabs the same as the dimensions of standard brick, the slabs can readily be built into the brickwork forming the end walls of the combustion chamber, thereby facilitating 60 the erection of the combustion chamber.

With the boiler assembly as above described, noise is also eliminated, the baffles provided by the slabs eliminating noise, and at the same time a long flue travel is provided and complete combustion takes place before the flue gases impinge 70 on the lower section of the boiler.

I claim as my invention:

1. A boiler assembly of the character described, comprising a combustion chamber including en- 75

- closing walls and a roof connecting said walls and composed of a plurality of flat slabs of a refractory material arranged side by side and supported at their ends on said walls, a boiler supported by said walls and extending over said roof, said slabs being each recessed at one corner only and being laid in inverted and offset relation to one another with said recesses in register whereby each pair of registering recesses provides a laterally extending opening through the roof of said combustion chamber through which the products of combustion are discharged against said boiler, said boiler being provided with a flue through which said products of combustion escape.
2. A boiler assembly of the character described, comprising a combustion chamber including enclosing walls made of bricks composed of a refractory material, and a roof connecting said walls and composed of a plurality of slabs of a refractory material arranged side by side, the end faces of said slabs being brick size and being built into opposite walls of said combustion chamber as a part of the brickwork thereof, said slabs being each recessed at one corner only and being laid in inverted and offset relation to one another with said recesses in register whereby each pair of recesses provides a laterally extending opening through the roof of said combustion chamber through which the products of combustion are discharged against said boiler, said boiler being spaced at its center above said roof and being provided with an upwardly extending flue through which said products of combustion pass.
3. A boiler assembly of the character described, comprising a combustion chamber including enclosing walls and a roof of a refractory material connecting said walls, a boiler including a lower horizontal cross bar supported at its ends on the walls of said combustion chamber, an upper main hollow boiler section arranged above said cross bar and means connecting said cross bar and main boiler section and providing a central restricted vertical jet providing internal communication therebetween, means for supplying water to said cross bar and an opening in the roof of said combustion chamber and directing the products of combustion against the underside of said cross bar at a place below said jet, said cross bar and main boiler section being formed to provide a flue through which the products of combustion escape.
4. A boiler assembly of the character described, comprising a combustion chamber including enclosing walls and a roof of a refractory material connecting said walls, a boiler including a lower horizontal cross bar supported at its ends on the walls of said combustion chamber and spaced above said roof, an upper main hollow boiler section arranged above said cross bar and a central nipple connecting said cross bar and main boiler section and providing a central restricted vertical jet providing internal communication therebetween, means for supplying water to said cross bar and an opening in the roof of said combustion chamber and directing the products of combustion laterally and upwardly against the underside of said cross bar at a place directly below said jet, said cross bar and main boiler section being formed to provide a flue through which the products of combustion escape.
5. A boiler assembly of the character described, comprising a combustion chamber including enclosing walls and a roof of a refractory material connecting said walls, a boiler including a lower horizontal cross bar supported at its ends on the walls of said combustion chamber and spaced above said roof, an upper main hollow boiler section arranged above said cross bar and a central nipple connecting said cross bar and main boiler section and providing a central restricted vertical jet providing internal communication therebetween, means for supplying water to said cross bar and an opening in the roof of said combustion chamber and directing the products of combustion laterally and upwardly against the underside of said cross bar at a place directly below said jet, said cross bar and main boiler section being formed to provide a flue through which the products of combustion escape.
6. A boiler assembly of the character described, comprising a combustion chamber including enclosing walls made of a refractory material and a roof connecting said walls and composed of a plurality of slabs of a refractory material arranged side by side, said slabs being externally recessed to provide a laterally and upwardly extending opening through the roof of said combustion chamber through which the products of combustion are discharged, a boiler including a lower horizontal cross bar supported at its ends on the walls of said combustion chamber, an upper main hollow boiler section arranged above said cross bar and means connecting said cross bar and main boiler section and providing a central restricted vertical jet providing internal communication therebetween and means for supplying water to said cross bar, said opening in the roof of said combustion chamber directing the products of combustion against the underside of said cross bar at a place below said jet, said cross bar and main boiler section being formed to provide a flue through which the products of combustion escape.
7. A boiler assembly of the character described, comprising a combustion chamber including enclosing walls made of a refractory material and a roof connecting said walls and composed of four slabs of a refractory material arranged side by side, the ends of said slabs being built into the opposite walls of said combustion chamber and being each recessed at one corner only and laid in inverted and offset relation to one another with said recesses in register whereby each pair of recesses provides a laterally and upwardly extending opening through the roof of said combustion chamber, a boiler including a lower horizontal cross bar supported at its ends on the walls of said combustion chamber, an upper main hollow boiler section arranged above said cross bar and a nipple connecting said cross bar and main boiler section and providing internal communication therebetween, and means for supplying water to said cross bar, said openings in the roof of said combustion chamber directing the products of combustion in opposing streams against the underside of said cross bar at a place directly below said jet, said cross bar and main boiler section being formed to provide a flue through which the products of combustion escape.
8. A boiler assembly of the character described, comprising a combustion chamber including side and end enclosing walls of a refractory material and a substantially flat roof connecting said walls and composed of a plurality of flat slabs of a refractory material arranged side by side

and supported at their ends on said walls, a boiler supported by said walls and extending over said roof in closely spaced relation thereto, said slabs being indented along one side to provide a plurality of openings in the roof of said combustion chamber, said openings extending at an angle to both the horizontal and the vertical to direct the products of combustion laterally into the space between said boiler and roof and directly against the underside of said boiler, said boiler being provided with a flue through which the products of combustion pass.

9. A boiler assembly of the character described, comprising a combustion chamber including side and end enclosing walls of a refractory material and a substantially flat roof connecting said walls and composed of a plurality of flat slabs of a refractory material arranged side by side and supported at their ends on said walls, a boiler supported by said walls and extending over said roof in closely spaced relation thereto, said slabs being indented at one corner to provide a plurality of openings in the roof of said combustion chamber, said openings extending at an angle to both the horizontal and the vertical to direct the products of combustion laterally into the

space between said boiler and roof and directly against the underside of said boiler, said boiler being provided with a flue through which the products of combustion pass.

10. A boiler assembly of the character described, comprising a combustion chamber including side and end enclosing walls of a refractory material and a substantially flat roof which is substantially flat on its upper and lower sides and composed of horizontal slabs of a refractory material connecting said walls, a boiler composed of a plurality of sections each having water legs supported directly on the tops of said side walls and the central part of said boiler being spaced a short distance above said roof, said roof of said combustion chamber having a plurality of openings extending at an angle to both the horizontal and the vertical to direct the products of combustion laterally into the space between said boiler and roof and against the area of said boiler delimited by its legs, said boiler sections being formed exteriorly to provide a plurality of circuitous passages through which the products of combustion pass.

HARRY S. MURPHY. 25
